CARL HAASE, OF SCHONAU, NEAR CHEMNITZ, GERMANY, ASSIGNOR TO HAUBOLDT A. G.,
OF CHEMNITZ, GERMANY, A JOINT-STOCK COMPANY OF GERMANY

MACHINE FOR SPINNING RAYON

Application filed November 4, 1930, Serial No. 493,447, and in Germany July 16, 1927.

My invention relates to improvements in machines for spinning rayon and more particularly in machines of the type in which for each spinning nozzle a plurality of bobbins are provided which are alternately thrown into position for winding the thread thereon, and in which further the driving mechanism for the bobbins is constructed so that the velocity of the bobbin is gradually reduced as the thread is wound thereon, so that the circumferential velocity of the bobbin or body of silk and therefore the tension of the thread remain constant. In machines of this type now in use two bobbins are mounted on a lever which is adapted to be rocked with the bobbins carried thereby into and out of spinning position.

The object of the improvements is to provide a machine of this class which is simple in construction and reliable in operation, and with this object in view my invention consists in operating the mechanism for varying the velocity of the bobbin and for rocking the bobbins into and out of spinning position from a common rotary shaft, which shaft will be described hereinafter as the counter shaft. The velocity of the said counter shaft can be varied within wide limits, and it controls the time of the filling operation of each bobbin, and the number of the rotations thereof needed for filling the same, it starts the exchanging of the bobbins whenever a bobbin has been filled, and it sets the operating mechanism for the bobbins so that at the beginning of a spinning operation the bobbin is rotated at the desired initial velocity.

For the purpose of explaining the invention an example embodying the same has been shown in the accompanying drawings in which the same reference characters have been used in all the views to indicate corresponding parts. In said drawings,

Fig. 1 is a sectional elevation taken on the line I—I of Fig. 3 and showing the spinning machine,

Fig. 2 is an elevation of the machine showing the gearings thereof,

Fig. 3 is an elevation viewed from the left in Fig. 1 and showing certain parts illustrated in the said figure,

Fig. 4 is an elevation of the machine showing particularly the gearings,

Fig. 5 is a somewhat diagrammatical plan view showing the relative position of the bobbins and the shafts for driving and rocking the same,

Fig. 6 is a detail view partly in section and on an enlarged scale and showing certain parts illustrated in Fig. 4, and

Fig. 7 is an elevation partly in section showing certain details.

In the example shown in the figures, on the frame of the machine a motor M is mounted which rotates at uniform velocity, and which drives a gear wheel M⁶ through the intermediary of a reducing gearing such as a worm gearing M¹, a shaft M², an intermediate gear wheel M³ and a gear wheel M⁴. On the shaft of the gear wheel M⁶ an eccentric M⁷ is mounted, and the rod M⁸ of the said eccentric is jointed to a lever M¹⁰ fixed to a shaft M¹¹ rockingly mounted on brackets M⁹ secured to the frame of the machine. The shaft M¹¹ is connected with a lever M¹² which engages a lever M¹³ rockingly mounted on a bracket M¹⁴ and carrying a pawl M¹⁵ engaging in a ratchet wheel M¹⁶.

To the shaft of the ratchet wheel M¹⁶ a worm M¹⁷ is secured which is in engagement with a worm gearing M¹⁸ secured to a shaft 1, which shaft is the counter shaft adapted gradually to reduce the velocity of the bobbins winding the thread thereon and to rock the member carrying the bobbins for moving the bobbins respectively into and out of a spinning position.

The mechanism for imparting rotary movement to the bobbins is constructed as follows:

On the counter shaft 1 a cam disk i is mounted which is in engagement with a lug i¹ secured to a lever i² rockingly mounted on the frame of the machine. The said lever is jointed to a link i³ guided at its top end in a sleeve i⁴ secured to the frame. To an eye i⁵ secured to the link i³ a rod i⁶ is connected which is jointed to a rockable lever i⁷. The lever i⁷ is connected by a link i⁸ with a lever k connected with the brushes of a subsidiary electric motor H, the connection being such

that by the rocking movement imparted to the shaft of the lever k by the mechanism so far described the brushes of the subsidiary motor H are shifted in circumferential direction, thus changing the velocity of the motor. Thus by the rotary movement of the cam i in the direction of the arrow P the velocity of the armature of the motor H is gradually reduced, and it is at its minimum when the parts and more particularly the cam i and the lug i^1 are in the positions shown in Fig. 4. Upon further rotation of the cam i in the direction of the arrow P the lug i^1 drops from the position shown in Fig. 4 on the portion of smallest radius of the cam i , whereby the brushes of the motor are returned into the position in which the motor has its highest velocity, the said velocity being gradually reduced until the parts are again in the position shown in Fig. 4.

When the parts are in the position shown in Fig. 4 and the lug i^1 passes from the highest part of the cam i to the part of smallest radius, the position of the bobbins is reversed.

As appears from Figs. 1 and 3 the bobbins are mounted in pairs a and a^1 on a common rockable carrier d . The machine is provided at both sides with sets of bobbins as is shown in Fig. 1 so that always two pairs of bobbins a and a^1 have the same movement and the same position. The carriers d are mounted on a shaft d^1 supported in a bearing member d^2 secured to the frame of the machine. To the shaft d^1 a worm gearing m is secured which is in mesh with a worm m^1 provided on a shaft n . On the spindle of each bobbin a worm gearing f^1 is mounted. In the operation of the machine the worm gearing f^1 of the bobbin located in its lowermost position is in mesh with a worm f^2 provided on a shaft f .

In the position of the parts shown in Fig. 1 the bobbin a is in spinning position. In machines of the type shown in Fig. 1 in which sets of bobbins are provided at opposite sides of the frame two shafts f are provided.

The carriers d are adapted to be rocked for reversing the bobbins a and a^1 from the counter shaft f through the intermediary of the rod i^3 . To the top part of the said rod i^3 a lug i^3 is secured, which cooperates with a pawl y rockingly mounted on a bell crank lever x supported on a bracket x^1 secured to a frame member x^2 , a spring y^3 being attached to the pawl y and tending to hold the same with its tail end in engagement with a pin secured to the lever x , and to rock the bell crank lever x with its left hand end downwardly. When the rod i^3 is shifted upwardly by the cam i the lug passes the pawl y which yields against the tension of the spring y^3 , and when thereafter the rod drops by reason of the lug i^3 falling from the portion of largest radius of the cam i on the portion of smallest radius, the lug i^3 rocks the lever x in clockwise direction. The left hand

end of the bell crank lever cooperates with a disk Q connected or made integral with a conical coupling member o , and normally it engages a lug q thereof, as is shown in Figs. 6 and 7. The disk Q and the coupling member o are axially shiftable and non-rotatable on a shaft e mounted on the frame of the machine. To the said shaft a ring e^1 is fixed which provides a support for a coiled spring r acting on the disk Q and tending to shift the same axially of the shaft e . On the shaft e a coupling member o^1 is rotatable which cooperates with the coupling member o , the spring r tending to force the coupling member o into engagement with the coupling member o^1 . Normally the disk Q is arrested by the bell crank lever x in the position shown in Fig. 7 in which the coupling members o and o^1 are out of coupling engagement. But when the bell crank lever x is rocked by the rod i^3 moving downwardly into position for releasing the disk Q , the spring r shifts the coupling member o into coupling engagement with the member o^1 .

The shaft of the subsidiary motor H carries a pinion g^3 which is in mesh with a gear wheel g secured to one of the shafts f . As has been described above, the said shaft drives the bobbins a , a^1 through the intermediary of worms f^2 and worm gearings f^1 at gradually reduced velocity.

To the shaft f a pinion g^1 is secured which is connected through gear wheels g^4 with a gear wheel g^2 mounted on the hub of the coupling member o^1 . Thus the said coupling member o^1 is continuously rotated from the subsidiary motor H .

When the rod i^3 moves downwardly the bell crank lever x releases the disk Q , so that the coupling members o and o^1 are thrown into coupling engagement with each other, and rotary movement is transmitted from the subsidiary motor H to the shaft e . To the said shaft a gear wheel e^2 is secured which is connected with the shaft n by a train of gear wheels e^3 . The shaft n is connected by means of a worm m^1 and a worm gearing m with the shaft d^1 on which the carriers d are mounted, so that the shaft d^1 is rocked through an angle of 180° when the coupling members o , o^1 are in coupling engagement. Thus the bobbins a and a^1 are reversed, the bobbin a^1 which before was in operative being set into spinning position, while the bobbin a on which the thread has been wound is brought into inoperative position in which it can be removed from the carrier and replaced by an empty bobbin. When the bobbins a or a^1 are in spinning position they rotate in a trough b applying a suitable treating liquid to the silk. After the bobbin has again been filled with silk the shaft d^1 is again rocked through an angle of 180° . Thereby the thread rocking through the thread guide e is torn and placed on the empty bobbin.

brought into spinning position. The operation of the parts controlled by the bell crank lever α and the disk Q is such that after the lug i^o has rocked the bell crank lever, and the lever α has released the lug q , the spring y^s returns the lever into the position shown in Figs. 4 and 6, so that upon further rotation of the disk Q the gradually ascending lug q engages the lever α , so that the coupling member o and the disk Q are forced to the right against the tension of the spring r .

As appears from the foregoing description a single controlling mechanism is provided for the sets of bobbins a , a^1 located at opposite sides of the machine, the said bobbins being rotated from the shafts f , f^2 driven from the subsidiary motor H through the intermediary of the gearing g^3 , g and the shafts f , f^2 driving the sets of bobbins located at opposite sides of the machine being connected with each other by suitable gear wheels shown in Fig. 4. Further, the said controlling mechanism is adapted to rock the carriers d of the sets of bobbins located at opposite sides of the machine, said carriers being respectively secured to the same shaft d^1 .

I claim:

1. In a machine for spinning rayon, the combination with a movable carrier adapted to support a pair of bobbins, means for moving said carrier to place either of said bobbins in operative spinning position, mechanism for rotating the bobbin thus rendered operative, means for varying the speed of rotation of said bobbin, and a movable cam and follower connected with both of said means for operating the same in timed relation.

2. In a machine for spinning rayon, the combination with a rockable carrier adapted to carry a pair of bobbins, of means for rocking said carrier for alternately throwing said bobbins into and out of spinning position, mechanism for rotating the bobbin occupying the spinning position, a rotary member, coupling mechanism for connecting said rotary member with said rocking means, a spring acting on one of the coupling members and tending to shift the same into coupling engagement with the other coupling member, an abutment member adapted to hold said spring actuated coupling member in non-coupling position, controlling mechanism adapted to throw said abutment member out of arresting position, and means controlled by the driven member of the coupling mechanism for returning said spring actuated coupling member into non-coupling position.

3. A machine for spinning rayon, comprising a rockable carrier adapted to carry a pair of bobbins, means for rocking said carrier for alternately throwing said bobbins into and out of spinning position, mechanism for rotating the bobbin occupying the spinning position, a rotary member, a coupling mechanism for connecting said rotary member with

said rocking means, a spring acting on one of the coupling members and tending to shift the same into coupling engagement with the other coupling member, an abutment member adapted to hold said spring actuated coupling member in non-coupling position, controlling mechanism adapted to throw said abutment member out of arresting position, and a cam connected with said spring pressed coupling member and adapted to engage said abutment member for retracting the spring pressed coupling member out of coupling position.

4. A machine for spinning rayon, comprising a rotary member adapted to carry a bobbin for winding thereon the thread, an electric motor for rotating said bobbin, means for varying the velocity of the rotation of said motor comprising a controlling cam member formed with a gradually ascending cam face and an abrupt portion, and a follower engaging said cam face and operatively connected with the motor brushes for shifting the position of the latter.

5. A machine for spinning rayon, comprising a rockable carrier adapted to carry a pair of bobbins, means for rocking said carrier for alternately throwing said bobbins into and out of spinning position, mechanism for rotating the bobbin occupying the spinning position, and common controlling means for gradually reducing the velocity of said rotating mechanism and for operating said rocking means, said controlling means comprising a rotary cam having a gradually ascending cam face and an abrupt portion connecting the portions of largest and smallest radii of said cam, a rod sliding on said cam and connected with said rotating mechanism and adapted, when moving from the portion of the cam of largest radius to the portion of smallest radius, to operate said rocking means.

6. A machine for spinning rayon, comprising a rockable carrier adapted to carry a pair of bobbins, means for rocking said carrier for alternately throwing said bobbins into and out of spinning position, mechanism for rotating the bobbin occupying the spinning position, an electromotor connected with said rotating means, coupling mechanism adapted to connect said electromotor with said rocking means and means including a rotary controlling member adapted gradually to vary the velocity of the rotation of said electromotor and to set said coupling means into coupling position.

7. A machine for spinning rayon, comprising a rockable carrier adapted to carry a pair of bobbins, means for rocking said carrier for alternately throwing said bobbins into and out of spinning position, mechanism for rotating the bobbin occupying the spinning position, an electromotor connected with said rotating means, coupling mech-

anism adapted to connect said electromotor with said rocking mechanism, a rotary controlling cam having a gradually ascending cam face and an abrupt portion connecting the parts of largest and smallest radii of said cam face, a rod engaged by said cam face, means connected with said rod for gradually reducing the velocity of said electromotor, and means including a device on said rod operative when the rod passes from the portion of the cam of largest radius to the portion of smallest radius for throwing said coupling mechanism into coupling position.

In testimony whereof I hereunto affix my signature.

CARL HAASE.
